J. M. BLANCO

VEGETABLE SLICER

Filed July 25, 1922

INVENTOR
J.M. Blanco

BY *J. Ledermann* ATTORNEY

UNITED STATES PATENT OFFICE.

JOSE M. BLANCO, OF NEWARK, NEW JERSEY.

VEGETABLE SLICER.

Application filed July 25, 1922. Serial No. 577,350.

To all whom it may concern:

Be it known that I, JOSE M. BLANCO, a citizen of the United States, residing at Newark, in the county of Essex and State 5 of New Jersey, have invented certain new and useful Improvements in Vegetable Slicers, of which the following is a specification.

This invention relates to vegetable slicers 10 and the main object is to provide a slicer useful for preparing vegetables or the like for the table or for culinary uses. The device has a cutting knife which is arranged so that the latter may be adjusted to give various sizes of chips.

Another object is to provide a vegetable slicer which has means for retaining the vegetables in contact with the knife and additional means by which the vegetable carrier returns to its original position after being urged in the required direction.

These and other objects will become apparent in the description below, in which characters of reference refer to like-named parts in the drawing.

Referring briefly to the drawing, Figure 1 indicates a front elevational view of the slicer showing particularly the means for guiding the vegetable carrier.

Figure 2 is a top plan view of the same showing the vegetable carrier at the end of the stroke.

Figure 3 is a sectional side elevational view thru the device.

Figure 4 is a fragmentary elevational view of the carriage showing the knife adjusting means.

Figure 5 is a top plan view of the modified type of knife.

Figure 6 is a side elevational view of the same.

Describing the drawing in detail, the numeral 1 indicates a platen having side frame members 2 formed therewith, and is provided with an angular slot 3 which extends across the carriage. Triangular channels 4 extend thruout the length of the side frames 2 on their mutually adjacent sides and above the platen 1.

50 A carrier plate 5 which has its edges formed into triangular guide surfaces 6, is slidably mounted in the corresponding channels 4 of the side frames 2.

A substantially rectangular magazine in-

tegral with the carrier plate 5, is open at one 55 of the end sides, and is provided with a cover 8 thru which a plunger rod 9 passes. The lower end of said plunger rod 9 has a feeding plate 10 secured thereto, the latter being urged downwardly by a coil spring 11 60 which is wound about the plunger 9 between the cover 8 and the said feeding plate 10. Keyways 12, cut into the opposing edges of the feeding plate, engage corresponding guides 13 which are formed vertically on 65 the side walls 14 and are provided for retaining the said feeding plate in vertical alignment and free from side play.

A handle member 15, rigidly secured to the upper end of said plunger rod 9, is provided for lifting the feeding plate to the top of the magazine when the latter is to be filled. When vegetables such as potatoes 16 are cast into the magazine the handle 15 is released and the feeding plate urges the said 75 potatoes thru a relatively large annular opening and into contact with the slicing knife 17 which is set into the slot 3 of the platen 1. The cutting edge 17 of the knife is raised above the inclined surface 18 of the platen 1, the lowest point of said surface being adjacent to the cutting edge of the knife.

Plates 19 are secured to the side frames 2 by the screws 19' and close the ends of the slot 3. The said plates are provided with 80 rectangular holes 20 and projections 21, the latter being somewhat above in alignment with the said holes.

The knife 17 has ears 22 projecting from its ends, which threadably receive the adjusting screws 23 the latter being suspended 90 from the projections 21.

Springs 24 are secured to the side frames 2 and the carrier plate 5 and urge the latter over the cutting edge 17 of the knife when 95 the said carrier plate is slid in the required direction.

Figures 5 and 6 illustrate a different type of knife and which is used when it is desired to cut the potato or vegetable into very small 100 pieces similar to granules. Said knife comprises a main body 25 upon which a plurality of ridges 26 are formed in such manner as to have the vegetable presented to it at an angle. The direction in which the carrier plate passes over the knife is illustrated 105 by the arrows in Figure 5.

In use the magazine is filled by lifting the

handle 15 and inserting the vegetables 16 beneath the feeding plate 10 which is then released and permitted to urge the said vegetables thru the opening provided in the carrier plate 5.

- 10 Alternately sliding the carrier plate 5 into the position shown in Figure 2, and allowing it to be returned by the springs 24 to the opposite end of the platen 1, will present the vegetables to the cutting edge 17 of the knife, whence the vegetables will be sliced to the thickness equivalent to the distance between the lowest point of the inclined surface and the cutting edge 17 of the knife 16.
- 15 The thickness of the slice to be cut can be controlled by manipulating the screws 23 in the proper direction, which will either raise

or lower the knife with respect to the inclined surface 8.

I claim:—

20 A slicing device of the class described comprising an angular slotted platen, a slicing knife mounted in said angular slot, plate members covering the ends of said slot having projections formed thereon, ears on said cutting knife, threaded screws connecting said plate projections and ears of said knife, said screws adapted to lift or lower said slicing knife, and means urging the vegetables into contact with the cutting edge of the 30 knife.

In witness whereof I, affix my signature.

JOSE M. BLANCO.
